UNITED STATES PATENT OFFICE.

EDWARD P. FOLLETT, OF ROCHESTER, ASSIGNOR OF ONE-HALF TO ABEL J. BIXBY, OF LYONS, N. Y.

LANTERN.

SPECIFICATION forming part of Letters Patent No. 241,953, dated May 24, 1881.

Application filed October 8, 1880. (No model.)

To all whom it may concern:

Be it known that I, EDWARD P. FOLLETT, of Rochester, in the county of Monroe and State of New York, have invented a new Improvement in Lanterns; and I do hereby declare the following, when taken in connection with the accompanying drawings and the letters of reference marked thereon, to be a full, clear, and exact description of the same, which 5 said drawings constitute part of this specification, and represent, in—

Figure 1, a side view; Fig. 2, a vertical central section of the lower part; Figs. 3 to 11, detached views.

15 This invention relates to an improvement in that class of lanterns in which the air, or a portion of it, to support combustion is brought down from the top through tubes opening into an air-chamber below or around the burner, 20 parts of which are applicable to other classes of lanterns; and the invention consists in the construction hereinafter described, and particularly recited in the claims.

A represents the lamp-fount, of any known 25 or desirable form; B, the air-chamber; C C, the tubes which lead from above and open into the air-chamber B in the usual manner; D, the burner, set in the top of the air-chamber beneath the deflector E. Around the deflector is the 30 rest or support F for the globe G, all in substantially the usual relation to each other.

The air-chamber B is made from a single disk of sheet metal, as seen in Fig. 10, its outer edge, b, turned down to form the outer wall and 35 set upon the top of the lamp-fount. At the center an opening is made for the burner, and the metal around this opening is turned downward to form a flange, d, and which corresponds to a central opening in the top of the lamp-fount, so that the flange b forms the outer wall, 40 flange d the inner wall, and flat portion e the top of the chamber B, the top of the lamp-fount f forming the bottom of said chamber B, as seen in Fig. 2. The space at the center within 45 formed by the flange d is made to correspond to the shape of the base h of the burner, and so that the burner will fit closely therein. By this construction the outer and inner walls and the top of the air-chamber are made in a single piece 50 of sheet metal, and at the same time forms the

seat for the burner. Preferably the lower edge of the flange d is turned inward, as at i, (see Fig. 10,) and so that the lower edge of the base of the burner will rest thereon as a bearing.

The burner D is constructed with a hook, n, 55 (see Fig. 6,) on each side, so as to set through corresponding slots, m, in the top of the air-chamber, and then given a partial rotation to bring the ends of the hooks beneath the top e, to secure the burner in its seat.

60 The deflector E is hinged to the top of the air-chamber, as at r, (see Fig. 2,) and forms a combustion-chamber around the burner. The top of the air-chamber is perforated within the combustion-chamber, forming an air-distributer for the inflowing air.

65 The wick-tube, as seen detached in Fig. 7, and in section Fig. 11, is divided vertically at the sides, each part formed with a slight flange at the edge, and each turned over at the top 70 to form a flange, s, in a horizontal plane around the top of the burner. This flange is perforated to admit sufficient air to the base of the burner to support combustion and turn or direct a greater portion of the air to the flame 75 above the base. The result of this is an increase or enlargement of the flame at the base, and consequently an enlargement above, it being understood that the perforations must be back from the edge of the wick-tube. This 80 flange then serves, in fact, as a spreader for the flame.

In the usual construction of removable globe-lanterns the cap or top is movable vertically, so as to set down upon the neck of the globe, 85 and locked in that position secures the globe in place. If the globe be a little too long, the pressure will be very great, if a little too short, then the globe will be loose and rattle; but even if it fits properly the expansion and contraction produced by heating the globe frequently causes the globe to break, because of the rigid and unyielding attachment at the top and bottom.

90 The device for adjusting the top is that secured in a patent granted to me April 15, 1879, and which consists of two spring-arms, G' G', which extend up through slots in the frame D', each constructed with a notch, i, which 95 engages the frame when the cap is down; but 100

when the two arms are disconnected from the frame then the cap, ring, or neck-holder may be raised, as seen in broken lines, Fig. 1.

I provide a yielding support for the globe, 5 in combination with the adjustable cap or ring, as follows:

H is a ring of elastic metal outside the deflector and hinged to the air-chamber, as at u. To the upper edge of this ring the globe-holder F is attached. This globe-holder consists of a ring of sheet-metal, (see Figs. 2 and 9,) attached by its inner edge to the upper edge of the ring H, and curved downward and outward, as seen in Fig. 2, its outer edge turned 15 upward to form a seat, w, for the globe. Numerous slits, x, are made from the outer edge of the holder radially inward, so that the outer edge of the holder forms a series of independent springs, upon which the globe will rest. 20 These springs, being independent of each other, yield to the unavoidable irregularities of the lower edge of the globe, and consequently insure a close fit of the globe entirely around its base. They also form an elastic holder, which 25 readily yields to any expansion of the globe, so that however firmly it may be held it is not liable to be broken, as is necessarily the case with rigid holders. The wick-adjuster shaft L extends outward through the side of the deflector and through the ring H below the globe-holder, as seen in Fig. 1, the deflector and ring H having a notch, so as to close down over the said shaft L. The burner is first set in place, then the deflector and the globe-holder turned down. 30 The notches therein passing out the adjuster-shaft prevent the burner from becoming detached by any accidental turning which might occur.

The guard is made detachable, and consists 40 of two parts joined at each side. Each part forms two semicircles, N. These two semicircles are made from a single piece of wire bent to bring the two semicircles into planes paral-

lel to each other—that is, one above the other—and so as to make a vertical connection, P, 45 between them at each side or end of the semicircles, as seen in Fig. 3. The two semicircles, so bent and connected, form one-half the guard, the vertical connection of the one half meeting the vertical connection of the other half 50 each side the globe. Then the vertical connections are joined by a piece of sheet metal, R, its edge turned around the vertical portion P, as seen in Fig. 4, which firmly unites the two parts so as to form a circular guard for the 55 lantern. The connections R are made to fit the outer surface of the tube C, and correspondingly inclined so as to slide down over the tubes to the position required for the guard, and as seen in Fig. 1. 60

I do not broadly claim a wick-tube made in two parts, nor do I broadly claim a wick-tube with a spreader at the base of the flame; neither do I broadly claim a lantern having a removable guard composed of concentric rings 65 of wire; but

What I do claim is—

1. In a lantern, the globe-holder consisting of a metal ring having its outer edge bent to form a seat for the globe, and radially slitted 70 from the outer edge to form independent springs upon which the globe will rest, combined with a vertically-movable cap or ring at the top arranged to set down upon the neck of the globe to hold it in place, or raised to remove the 75 globe, all substantially as described.

2. A lantern-guard made in two parts, each part consisting of two concentrical semicircles, 80 N N, with vertical connections P, made from a single piece of wire, and the said two parts joined at the said vertical connection, substantially as described.

EDWARD P. FOLLETT.
